JAR WRENCH

Philip F. Marsella and Ferdinando Marsella,
Seneca Falls, N. Y.

Application April 26, 1938, Serial No. 204,452

1 Claim. (Cl. 81—3.1)

This invention relates to a jar wrench, and it is a particular object of the invention to provide a device of this kind which can be employed to advantage in either loosening or tightening screwable caps, such as used in connection with fruit jars, bottles, etc.

Another object of the invention is to provide a device of this kind which can be readily adjusted for use in connection with caps of various sizes and wherein the jaws are also so constructed as to permit the tool to be employed to advantage in the removal of rubber gaskets and the like.

The invention also has for an object to provide a device of this kind constructed and assembled in a manner to allow the same to be put to various uses other than the loosening or tightening of caps.

The invention consists in the details of construction and in the combination and arrangement of the several parts of our improved jar wrench whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view in side elevation of a jar wrench constructed in accordance with an embodiment of our invention;

Figure 2 is a view in bottom plan of the device as illustrated in Figure 1;

Figure 3 is a view in elevation taken at the side of the wrench opposite from that illustrated in Figure 1;

Figure 4 is a sectional view taken substantially on the line 4—4 of Figure 2;

Figure 5 is an enlarged fragmentary sectional view taken substantially on the line 5—5 of Figure 1;

Figure 6 is a view in top plan of a plate herein employed and unapplied;

Figure 7 is a view in side elevation of the plate as illustrated in Figure 6.

As disclosed in the accompanying drawings, A denotes an elongated shank which is substantially U-shaped in cross section and comprises a back or intermediate wall 1 and the side walls 2 and 3. The free longitudinal margin of the wall 2 is provided therealong substantially its

entire length with an inwardly disposed flange 4. The forward end portion of the wall 3 is transversely enlarged to provide a plate 5 and this plate 5 projects a slight distance beyond the adjacent end of the shank A proper to provide 5 an offset jaw 6.

The working edge of this jaw 6 is substantially at right angles to the longitudinal axis of the shank A and is disposed on a slight inward curvature with the working margin of the jaw 10 formed to provide gripping teeth 7. It is to be noted that the working edge of this jaw 6 is formed to provide an outer sharp corner 8 for a purpose to be hereinafter more particularly referred to.

Snugly but slidably engaging within the shank A between the side walls 2 and 3 thereof is the movable shank B also U-shaped in cross section and comprising an intermediate wall 9 and the side walls 10 and 11. The wall 11 of the shank 20 B has close contact with the wall 3 of the shank A while the wall 10 of the shank B has close contact with the wall 2 of the shank A with the intermediate plate 9 of the shank B underlying the flange 4 of the shank A. The free longitudinal margins of the walls 10 and 11 have close contact with the intermediate wall 1 of the shank A whereby the intermediate wall 9 of the shank B is materially spaced from the intermediate wall 1 of the shank A.

The inner surface of the intermediate wall 9 of the shank B has formed a major distance therealong the rack teeth 12 with which engages the outer or free pointed extremity of a pawl 14. This pawl 14 is pivotally supported, as at 15, by 35 and between the inwardly disposed side flanges 16 defining the longitudinal side margins of an elongated lever 17.

This lever 17 is disposed rearwardly and longitudinally of the shank A and the forward portions of the flanges 16 of the lever 17 are pivotally engaged, as at 18, with the outstanding ears 19 provided at the opposite sides of a slot 20 provided in the forward portion of the wall 1 of the shank A.

The pawl 14 is directed through this slot 20 and is constantly urged in a direction for proper engagement with the rack teeth 12 through the medium of a spring 21. As herein disclosed, the spring 21 has one end portion bearing against 50 the lever 17 with its opposite end portion bearing against a lateral extension 22 carried by the pivoted extremity of the pawl 14. An intermediate portion of this spring 21 is coiled, as at 23, around the pintle 15. While this spring 21 55

operates to urge the pawl 14 toward the intermediate wall 8 of the shank B it also serves to urge the lever 17 in a direction away from the shank A. However, upon depression of the lever 17, or swinging movement of said lever toward the shank A, the pawl 14 will cause the shank B to move inwardly of the shank A to a predetermined distance and, of course, the extent of such inward movement of the shank B will be determined by the proper manipulations of the lever 17.

The side wall 11 of the shank B is continued by a forwardly or outwardly directed plate 24 which is so formed to be at its outer portion of a width substantially equal to the width of the jaw 6. This plate 24 is formed to provide a reverted jaw 25 inwardly offset with respect to the plate 24 sufficiently to bring the jaw 25 into a position substantially coplanar with the jaw 6. The working edge of the jaw 25 is also disposed on an inward curvature and said edge or margin is provided with the gripping teeth 26. The outer corner of the working edge of the jaw 25 is also pointed, as at 27, for coaction with the pointed corner 8 of the jaw 6 as will hereinafter be more particularly referred to.

The plate 24 and the adjacent portion of the wall 11 of the shank A have pressed outwardly therefrom the strengthening or reinforcing rib 28.

The rear extremity of the intermediate plate 8 of the shank B has struck outwardly therefrom a lug 29 for contact with a stop lug 30 suitably positioned at the rear portion of the plate 5. This stop lug 30, in the present embodiment of our invention, is struck from the inner lower corner of a plate 31 held to the inner face of the plate 5 by the suitably positioned screws 32. This plate 31 has a lower or inner straight edge 33 which, when the plate 31 is applied, closely approaches the adjacent marginal portion of the intermediate plate 8 of the applied shank B thus providing further means for maintaining the shank B in proper assembly with the shank A.

The outer longitudinal marginal portion of the plate 5 in close proximity to the jaw 6 is formed with a pair of spaced notches 34 in which engage marginal portions of a substantially U-shaped arm 35 provided at the upper and outer corner 50 of the plate 31 and which arm is disposed transversely of such plate 31.

The plate 31 is also formed to provide a cutting blade 36 extending across the U-shaped arm 35 and in desired spaced relation with respect thereto. This blade 36 is of a type used in the opening of cans or kindred sheet metal containers.

The outer rear portion of the plate 31 also carries a pair of disks 37 to be employed in the sharpening of knives and to facilitate the desired use of these disks 37, the plate 31 is notched or recessed at 38 to allow effective engagement of a knife with said members 37.

The inner lower portion of the plate 5 is disposed on a suitable curvature, as at 39, for coaction with a rearwardly disposed hook member 40 formed on the plate 31 whereby the device can be effectively employed in the removing of bottle caps and the like.

Overlying the lower forward portion of the plate 31 and held thereto by certain of the screws 32 is a block 41 which, as herein disclosed, constitutes a pencil sharpener. The forward portion of this block 41 extends below the free end portion of the arm 35 hereinbefore referred to.

The rear portion of the shank A has pivotally

engaged with the intermediate wall 1 thereof a disk 42 carrying a plurality of glass cutting wheels 43. By proper rotation of the disk 42 the cutting wheels 43 may be selectively caused to extend beyond the adjacent end of the wall 1.

This rear end portion of the shank A has pivotally engaged therewith a guard 44 which, when in one position, extends across the rear end of the shank A to afford protection against injury by a projecting cutting wheel 43.

It is believed to be apparent from the foregoing that upon manipulation the shank B may be readily drawn outwardly with respect to the shank A in order to allow the jaws 6 and 25 to be used in connection with screw caps of various sizes. It is also believed to be apparent that upon manipulation of the lever 17 the shank B will be moved inwardly of the shank A to cause desired effective clamping of the cap between the jaws 6 and 25.

As is well known, it is the general custom to employ in connection with screw caps a sealing gasket having a projecting lip. To facilitate the removal or breaking of this gasket, this projecting lip can be readily engaged between the points 8 and 27 of the jaws 6 and 25 respectively.

From the foregoing description it is thought to be obvious that a jar wrench constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

A wrench of the character described, comprising an elongated handle shank shaped from a single sheet of material and of substantially U-shaped cross-section including side plates and an intermediate plate, one side plate being extended at one end longitudinally of the shank 45 beyond the other plate and the intermediate plate and being widened through a portion of its length, the said extended and widened portion having its forward edge formed to provide a jaw, a shiftable shank of substantially equal length to 50 and slidably mounted in the handle shank and shaped from a single sheet of material and of substantially U-shaped cross-section including side and intermediate plates, the side plates of the shiftable shank being disposed against the inner 55 sides of the other side plates and the intermediate plates being in spaced relation, a side plate of the shiftable shank being longitudinally extended at the end adjacent said jaw and shaped to form a jaw coacting with the first jaw, a plate 60 secured against the inner face of the said widened portion of said handle shank side plate and having an edge engaging the adjacent side plate of the shiftable shank to retain the shanks in sliding assembled relation, a handle pivotally carried 65 on the handle shank, a rack extending lengthwise of the inner side of the shiftable shank intermediate plate, and a spring pressed pawl pivotally attached to the handle and extending through an opening in the intermediate plate of the handle 70 shank for engagement with said rack to effect relative movement of the shanks and jaws on oscillation of the handle.

PHILIP F. MARSELLA.
FERDINANDO MARSELLA. 75
